UNITED STATES PATENT OFFICE

2,638,975

COMBUSTION CHAMBER FOR GASEOUS FUELS

Michael F. Berry, Cleveland, Ohio

Application April 23, 1948, Serial No. 22,844

3 Claims. (Cl. 158—115)

1

This invention relates to improvements in heating devices, and more particularly to an improved burner for natural, manufactured, mixed or liquefied petroleum gas which is particularly useful in converting existing solid fuel furnaces for burning gas.

Although there are many of the so-called "conversion burners" on the market, they are not always as efficient as could be desired, both from the standpoint of fuel consumption and from the standpoint of heat transferring efficiency when used in conjunction with the type of furnaces with which these devices are ordinarily installed. That is, a large amount of the heat of combustion goes up the stack and is lost due to the inefficiency with which the heat is transferred to the wall of the furnace.

Still another disadvantage of the prior art devices reside in their inability to operate properly with varying gas pressure. A burner designed to operate on one pressure performed inadequately on a lower pressure or not at all. This was particularly undesirable since, usually, at the time when the heat is needed the most, the gas pressure is lowest.

Furthermore, during the cycling of the burner, turning on and off, it is not uncommon at the present time for the burners to shut off or turn on with a minor explosion, resulting in the extinguishing of the flame as well as being annoying in its sound.

Other disadvantages resided in the provision of structures which were often too complicated for the average furnace man to install, repair or service and sometimes required extreme mutilation of the furnace and resulted in the installation being a major operation.

By my present invention, I have provided a burner which operates in a highly efficient manner with varying pressures of gas. Furthermore, the structure is so designed that even the more unskilled of furnace men can install them properly. The burner is so constructed that a minimum amount of work is required during the installation which can be made quickly and easily. After installation, the structure is such that it is readily accessible for repair or replacement of the parts. The "blow back" or explosion concomitant to turning off of the burner is completely eliminated and thus the pilot is never blown out. All of this results in a burner, which, when once installed and adjusted, will give long periods of desirable operation without attention.

Still other advantages of the burner of my invention and the invention itself will become

2

more apparent from the following description of an embodiment thereof, which description is illustrated by the accompanying drawings.

In the drawings:

5 Fig. 1 is a perspective view of the burner of my invention complete with the controls and pilot light;

Fig. 2 is an enlarged plan view of the burner;

10 Fig. 3 is a perspective view of the burner per se with the ceramics broken away to show the interior construction;

Fig. 4 is a plan view of a spider which is used in conjunction with the riser to support the burner ceramics;

15 Fig. 5 is a section taken on the line 5—5 of Fig. 4;

Fig. 6 is a section taken on the line 6—6 of Fig. 5;

20 Fig. 7 is an exploded plan view of the ceramic supporting pan removed from the spider;

Fig. 8 is a top plan view of the spider and its ceramic supporting pan, showing the location of the pilot lights;

25 Fig. 9 is a view, partially diagrammatic and partially in plan of the lower ceramic for the burner;

Fig. 10 is a fragmentary section of one of the lower ceramic parts taken on the line 10 of Fig. 9;

30 Fig. 11 is an elevational view of one of the upper ceramic segments;

Fig. 12 is a similar view of one of the upper ceramic parts rotated 90 degrees from that of Fig. 11;

Fig. 13 is a bottom plan view of the ceramic section;

35 Fig. 14 is a plan view of a ceramic guard and flame dispersion element;

Fig. 15 is a vertical medial section through the burner along the lines indicated by the lines 15—15 of Fig. 14 and showing the position taken by the flame dispersion element; and

40 Fig. 16 is an enlarged elevational view of one of the pilot lights and its accompanying thermocouple.

45 As previously stated, the burner of my invention is particularly adapted for use in converting solid fuel burning furnaces to gaseous fuel burning furnaces. It will be appreciated, however, that in the broader aspects of the invention, it is useful for the replacement of the burners in present gas fired furnaces or in original equipment. The invention will, however, be explained in connection with its use as a conversion burner.

46 As best shown in Fig. 1, a base 10 of tripod formation is provided in which is supported a

threaded rod 11, the same being secured in adjusted position by a lock nut 12. The rod in turn supports the burner, being threaded into a boss 13 Fig. 3 integral with an elbow 14 of the mixing chamber. Although in this instance the rod is shown as having right hand threads, it may be desirable to provide a right hand thread on one end and a left hand thread on the other end to assist and facilitate in the final adjustment of the burner for height after installation. Different length rods can be used if desired.

The elbow 14, Fig. 1, has one end disposed in a horizontal position and is provided with a threaded bell 16 for the reception and support of the outer horizontal mixer pipe 17. The other end of the elbow extends vertically and is tapered at 18 for close fitting engagement with the flared end 19 of the riser pipe 20.

The lower end of the riser pipe is notched at 22, adapted for seating engagement with a pin 23 carried by the elbow Fig. 1. The position of the pin and notch are such that the riser cannot be assembled on the pipe in the wrong manner. The taper is such as to provide a tight joint when the riser is in place on the elbow.

The riser 20 is also provided with a notch 24 in its upper end for cooperation with the ceramic support spider later described.

As illustrated in Fig. 1, the outer mixer pipe 17 extends longitudinally toward and into a housing 26 which houses the gas control valve, not shown.

As best shown in Fig. 2, the riser supports a spider, which in turn supports a baffle and a ceramic support plate, and the ceramic support plate supports the ceramics which comprise the combustion chamber.

The spider, Figs. 4 to 6 inclusive, includes a hub 50 from which radiate four arms, 51 to 54. The hub is provided with a bore 56, of a diameter to allow the hub to be telescoped over the upper end of the riser 20. The upper end of the bore is provided with an inwardly extending flange 57 adapted to seat on the upper end of the riser. The flange 57 has a downwardly extending boss 58, of curved formation, which, when the hub is in proper position on the riser, seats in the notch 22 on the riser. Thus the notch 22 on the bottom of the riser engaging with the pin 23 determines the correct position of the riser and the notch and boss 24 and 58 determine the position of the spider assuring that they cannot be readily assembled in the wrong position. It may be made of any suitable metal, such as cast iron.

The arms 51, 52, 53 and 54 are each provided with bosses 61, 62, 63 and 64 in which are disposed vertically extending pins 61', 62', 63' and 64'. The pins 61', 62' and 63' are disposed the same distance from the center of the spider, but the pin 64' and the boss 64 are disposed at a greater distance from the center. In this instance, on 4" and 4½" radii respectively. Likewise, the arm 54 is longer than the other arms to provide support for the pilot light as will later appear.

The ceramic supporting member may also be made of cast iron, and as best shown in Figs. 7 and 8 is generally in the form of a plane bounded by two concentric circles. It is formed of two parts 68 and 69' by dividing along the diameter. The periphery is provided with a vertically extending flange 161—162. Ribs 65 are provided which extend inwardly from the flange parallel to a radius or at a slight angle thereto and slightly displaced therefrom as shown, and between the ribs is a groove 65' which extends from the inner diameter or opening across the plate through the

flange 161. The plates are adapted to be seated on the arms of the spider and are provided with openings 71, 72, 73 and 74 for engagement with the pin 61' to 64' inclusive. It will be noted that the opening 74 is displaced greater distance from the center than the others for alignment with the pin 64'. Thus, the plates cannot be incorrectly placed on the spider if the pins are to go into their respective openings in the plate. This assures proper alignment of the plates on the spider.

As best shown in Figs. 2 and 3, a sheet metal baffle plate 66 which is of the same general contour as the ceramic support plate, but larger, is provided, this being placed on the spider prior to the placement of the ceramic support plate. The baffle may vary in size, depending upon the size of the fire pot, it being preferable that it extend relatively close to the fire pot wall. A notch, or gap, is provided in the baffle at 67 to allow the pilot to extend therethrough. It can be made in two parts if desired, since this facilitates assembly, particularly where the door opening of the furnace is small.

The ceramic combustion chamber is supported by the plates 68 and 69'. It is formed in parts which cooperate with each other to form a chamber for distribution of the gasses and to effect the proper combustion thereof, as well as to direct the flame toward the wall of the furnace. The parts include lower sections which rest on the support plate and upper sections which rest on the lower sections.

The lower sections, Figs. 1, 3, 9 and 10, as best shown in Figs. 9 and 10, preferably comprise three separate sections 75, which are arranged in abutting relationship to form a ring. The bottoms 76 of the sections are substantially flat for seating engagement with the plates 68—69'. Each bottom wall is formed with a groove 79 which extends across the bottom and into which the ribs 65 are adapted to extend. It will thus be apparent that the position of the ceramics on the support plate is determined by the engagement of at least one of the ceramics with the ribs so that proper orientation is assured. This channel and the ribs, as well as the groove 65', provide a duct extending from the inside opening of the ceramics to the periphery for cooperation with the pilot lights as will later more clearly appear.

The upper surface of the ceramic ring, as can best be seen in Fig. 10, is inclined downward from the outer wall to the inner wall, and is provided with a groove 80 which extends around the ceramic spaced from the inner wall. The surface between the groove and the inner wall provides a ridge 81 which, together with the groove, is a supine 8. The upper surface, from the outside wall 69 into the groove 80 is provided with a plurality of channels or grooves 83 extending substantially tangentially to the central opening in the spider 50. The channels are deeper toward the outer ends, being at this point of U shape, the legs of the U shortening towards the inner end of the channels so that the channels which intersect the groove 80 at its center are substantial semi-circular at this point as is most clearly shown in Fig. 10. The channels are substantially equally spaced except at the point approximately midway between the ends of the sections, where instead of a channel there is provided an upwardly extending lug 85; this lug may be of rectangular form and extend from the outer edge to the groove 80 and serves as a locator lug for the upper ceramics. The tangential grooves, as

will more clearly appear later, cooperate with similar grooves in the upper ceramic to provide the burner ports.

The upper ceramic is preferably made in two parts 90 divided vertically along the diameter 91, and fits onto the lower ceramics. The details of the construction are clearly shown in Figs. 11 to 13 inclusive. Each of the faces 91, which extends vertically along the diameter is provided with a semi-cylindrical tongue 92 which extends from the periphery to the center, and with a semi-circular groove 93 which extends from the tongue 92 to the other edge. Since both parts of the ceramics are made alike, the tongues and grooves interlock when the parts are placed together to prevent shifting of the parts in a vertical direction at the diameter.

The top surface 102 is substantially flat. The bottom surface is so shaped and cooperates with the lower ceramic to form the combustion chamber.

The center of the ceramic is provided with a downwardly extending curved boss 95 which is surrounded by an annular channel 96, a section, as shown in Fig. 12 from the center to the edge being a supine S curve. The outer edge of the channel 96 terminates spaced from the outer edge of the ceramic, and the surface 97 in the outer zone, between the channel 96 and the periphery slants upwardly at the same angle as the downwardly sloping surface of the lower ceramic. This surface is likewise provided with a plurality of tangentially extending grooves or channels 99 corresponding to the channels 87 in the lower ceramic ring 75, which, in this instance, are of substantially equal depth throughout their length. These channels intersect the channel 96.

The upper ceramics rest upon the lower ceramics, as best shown in Figs. 1 and 3. The interlocking of the tongues and grooves 91-92 with each other prevents the shifting of the parts relative to each other and the engagement of the downwardly slanting face 98 of the upper ceramic with the slanting face of the lower ceramic holds the upper ceramic parts together and in place. The lugs 85 on the lower ceramic engage in the channels 99 and assure that the channels 99 line up with the channels 89 to provide passages of substantially elliptical cross section extending tangentially from the channel 96 to the periphery of the assembled ceramics. The boss 95 extends opposite to the outlet opening on the upper end of the riser tube 20 as is most clearly shown in Fig. 3.

A modification of the invention is illustrated in Fig. 15 wherein means is provided to prevent any possibility of a deteriorating ceramic from falling into the riser, and also providing for more efficient ignition.

To this end, I provide a member shown in plan in Fig. 14 which includes a center body 101 having a depression or cup 103 in its center and which may follow very closely, if not exactly, the conformation of the boss 95. This member is preferably made of cast iron and thus provides a downwardly extending boss which is disposed opposite to the riser 20.

The member is provided with two radially extending legs 105 which curve downwardly at 106 adapted to seat in the groove 89 of the lower ceramic. A third leg 108 is provided and is formed to provide a channel which is relatively wide at 107 and merges with the narrow portion 108. The cross section of both parts is substantially inverted U shape, and the outer portion 108

is adapted to extend through one of the passages 83-99, the end 108 extending tangentially in the same manner as do the ports. The lower edges 109 of the leg 108 are adapted to rest on the bottom of the passage. This leg, therefore, provides a liner for that passage which extends to the pilot light, preventing parts of the ceramic, which might in time disintegrate, from blocking the passage and providing a more direct route from the pilot to the center of the burner.

Likewise, the center portion 103 prevents the flames from directly engaging the boss 95 in the upper ceramic protecting that ceramic and preventing the particles from falling into the riser.

Ignition of the gas in the burner is effected by a pilot light system which includes a pilot light disposed outside the burner and one inside the burner in such a manner that complete ignition is had, avoiding the usual puffing or exploding common when lighting the burners.

As previously stated, the spider (Fig. 4) has one arm (54) which is longer than the others. This arm, as best shown in Figs. 1, 2, 3, 8 and 9 extends beyond the ceramic support members 60-61. The pilot lights are supported from the arm by brackets 110 and 111 which, as shown in Figs. 3 and 16, comprise a hooked portion 112 adapted to be slipped over the arm 54 and having a forked part 113 for engagement with a pin 114 on the arm 54. This determines the positioning of the bracket on the arm as does the pin 115 for the bracket 111.

Opposite to the hook part, there is a depending portion 116 having an outwardly extending foot 116' to which the pilot light tube 117 is attached. The lower end of the tube 117 is threaded, extending through the foot 116' and is locked in position by nuts 118 on the opposite sides of the foot. The tube 119 from the gas supply is threaded to the end of the pilot tube at 131. The bracket and the pilot light are assembled prior to installation on the arm, the length of the bracket portion 116 being such that the height of the pilot is predetermined. The same provisions are made for the pilot 111. As best shown in Fig. 15, the outer pilot is positioned just below and opposite to the channel 108 while the inner pilot is positioned at approximately the level of the top end of the riser tube.

The controls for the burner include an element associated with the pilot light which prevents the gas being turned on if the pilot light should fail. A preferred form of a device is a thermocouple 125 which is supported by a bracket 118 on the pilot tube, this bracket being adjustable as to height by a screw 132 which extends through the bracket against the tube. The thermocouple is likewise adjustable in the bracket and is held in place by the screw 133. Electrical connections from the thermocouple are through the conduit 140. Although the thermocouple is illustrated, it is apparent the other thermally responsive devices could be used such as a conventional bimetallic element which operates a pair of contacts to make and break a circuit. A number of such devices are available on the market and the specific construction thereof forms no part of the present invention other than as hereinafter specifically described.

The top of the pilot tube is shaped in the form of a frustum of a cone and is provided with a port 135 which opens toward the thermocouple and a second port 136 which opens toward duct 108. The two parts are connected by a narrow slit 137. The flame from the port 135 is directed

toward the thermocouple and the one from the port 136, toward the duct 108.

In this particular instance, the thermocouple, when heated by the flame, generates sufficient voltage to hold a magnetic valve open. Should it become cool, the voltage decreases and the valve is released and cannot be opened, until opened manually, when the pilot is relit.

Preferably, only one thermocouple control is used as shown. The gas supply for the inner pilot 111 is connected in the supply line between the magnetic valve and the main burner valve.

The device may be installed in a furnace by simply removing the grates and their controls and the ash pit door. The base 10, together with the elbow 14 and the tube 17, are first set in position. The riser 20 is then placed in position and the remainder of the burner parts assembled as described.

The control box with its associated controls is then installed, the tube 27 being telescoped into the tube 17. The pilot lights are assembled in the manner shown, they being connected to the gas line ahead of the main burner valve.

Lighting of the pilot is effected by the lighter tube 200 which extends from the port 201, a valve control 202 being provided all in a manner well known to those versed in the art.

Preferably, the ceramics are placed in position last after the pilot lights are in place. As previously stated, the design is such that there is only one easy way for the parts to go together and a set of very simple instructions enable the most unskilled to make the installation.

After the installation is complete, the pilot lights are then lit, by holding the magnetic valve manually until the heat from the pilot against the thermocouple causes enough voltage to be generated to retain the magnetic pilot light valve in the open portion. The inner pilot light is preferably provided with two ports, one of which is directed toward the duct 65', and the other toward the top of the riser. When the outer pilot is lit, the gas from the inner pilot is directed through the duct 65' and is ignited by the outer pilot.

The gas coming up through the riser hits the boss 95 or in the case of Fig. 15, the member 103, which is coaxial with the riser and causes an even distribution of the gas toward all sides. Part of the gas escapes through the port or duct 108 and is ignited by the outer pilot and at approximately the same time or just prior thereto ignition occurs from the inner pilot. The ignition is quiet, complete and without explosion, since there is no opportunity for the combustible mixture to accumulate prior to ignition.

The contour of the inside of the chamber is such that the gas hits the boss 103, then swirls upward into the channel 96 after which it is directed downward into the groove 80 which causes the burning mixture to turn back upon itself and then to pass outward through the tangentially arranged ports toward the furnace wall. The primary combustion occurs inside the chamber, and the combustion is completed by the secondary combustion after the burning mixture leaves the ports. I have found that with natural gas such as is obtained in Ohio, a temperature of 1490 degrees is reached at the ports. The hot gases forced out of the ports of the burner are directed against the furnace walls so that the heat in the gases is absorbed by the walls and transferred through them to the fluid used for heating the rooms.

The ceramics which may have a combined

weight of as much as 37 lbs. provide considerable body for the storage of heat and retain the heat for some time after the burning ceases. This is a desirable feature, particularly in conversion burners since they are most often used in gravity operated furnaces. The carry-over time for the heat is thus extended and the off cycle, or cold period, is lessened.

By constructing the ceramics as described, their life is materially increased because there is no cracking during the heating and cooling periods since the component parts are free to expand and contract relative to each other. Furthermore, although this expansion and contraction does occur, the parts always retain the same relative position the top ceramics being prevented from shifting vertically by the tongue and groove connection and being held toward each other by the slanting surface connection with the lower ceramics. The top ceramics cannot shift circumferentially so as to cause the ports turned by the top and bottom grooves due to the introduction of the lugs or bosses 85 on the bottom ceramics with the grooves in the top ceramics. The bottom ceramics are retained in position by the flanges 62-63 and the ribs 65. Thus, all the parts, when once properly assembled, retain their position and can only be moved therefrom intentionally.

When the burner is shut off the two pilot lights keep the flame burning until the last of the combustible mixture is burned, thus preventing the minor explosion or "bloop" commonly heard when burners shut off.

Having thus described my invention, I am aware that numerous and extensive departures may be made therefrom without departing from the spirit or scope of the invention as defined by the appended claims.

I claim:

1. A combustion chamber for a burner comprising a metallic base ring, a lower combustion chamber ring comprising two or more sections supported loosely on the base ring, a cap for the combustion chamber comprising at least two sections for seating engagement on said combustion chamber ring and means on the combustion chamber ring and cap for interlocking engagement with each other to hold the same in position, said combustion chamber ring and cap being formed with cooperating grooves extending from the interior of the chamber to the exterior to provide fuel combustion exhaust ports, the axes of said ports extending tangentially to a circle concentric with the combustion chamber ring but within the circumference thereof, said cap being formed with an annular channel to provide a combustion chamber wherein the products of combustion are caused to assume a tortuous path through the burner, and a protecting member disposed in said chamber having a downwardly extending center portion and legs extending therefrom for engagement in at least some of said grooves to support said member adjacent the top of the chamber.

2. A combustion chamber for a conversion burner arranged to be connected to a riser tube for conducting a combustible mixture to said chamber comprising a base for said chamber comprising a metallic ring shaped member having a peripheral flange, a first ceramic member comprising a plurality of segments disposed on said base in engagement with said flange and formed with upper surfaces which slant downward toward the center, a second ceramic mem-

ber comprising at least a pair of members having interlocking tongues and grooves for engagement with each other and having a lower surface slanting downward toward the center for engagement with said first ceramic member, said members being formed to cooperatively form a combustion chamber with ports extending therefrom and opening exteriorly of the chamber, a metallic member having a downwardly extending rounded center portion disposed opposite to the end of the riser tube for dispersing the flame and guarding said second ceramic member from direct impingement of the flame, legs for said member in engagement with the lower ceramic member for supporting the guard adjacent the top of the chamber.

3. In a furnace burner adapted for use with a fuel mixing mechanism; comprising a combustion chamber adapted to be connected to said fuel mixing mechanism and including a support member, a base plate mounted on said support member, a circumferential rim on said base plate, a pair of substantially radial ribs on said base plate defining a channel formed therein, said combustion chamber comprising a plurality of ceramic members supported on said base plate to provide a lower combustion chamber element, said members resting on said plate within said rim and being thereby held in a predetermined lateral position on said plate, at least one of said members being formed with a groove on its lower surface adapted to embrace said ribs to close the channel formed thereby and to locate said combustion chamber element angularly on

said base plate, a pilot light mounted on said support plate adapted to burn opposite the outer end of said channel, an upper portion for said combustion chamber comprising at least two upper ceramic members, said upper and lower members being formed so that the lower members hold the upper members in position, said ceramic members being formed to provide a primary combustion chamber and burner ports extending through said members from said chamber.

MICHAEL F. BERRY.
